ROSS J. ELLSWORTH, OF WOODSTOCK, ILLINOIS, ASSIGNOR TO HOLMES DISAPPEARING BED COMPANY, OF WOODSTOCK, ILLINOIS, A CORPORATION OF ILLINOIS

COLLAPSIBLE BED

Application filed July 5, 1927. Serial No. 203,548.

This invention relates to collapsible beds and has for its object a construction wherein the bed elements may be disassembled to occupy a relatively compact and small space 5 for storage purposes when the bed is not in use.

With the above and other objects in view, as will be apparent, this invention consists in the construction, combination, and arrangement of parts all as hereinafter more fully described, claimed and illustrated in the accompanying drawings wherein:

Fig. 1 is a plan view of a bed constructed in accordance with the present invention, 15 fully assembled and mounted.

Fig. 2 is a transverse section taken along line 2—2 of Fig. 1 illustrating the connection between the end rails and the supporting structure.

20 Fig. 3 is a longitudinal section taken along line 3—3 of Fig. 1 and illustrates the connection between a side and end rail.

Fig. 4 is a section taken along line 4—4 of Fig. 1 longitudinally through one of the 25 end rails.

Fig. 5 is a similar section taken along line 5—5 of Fig. 1 to illustrate the mounting of an end rail.

Fig. 6 is a view similar to Fig. 1 illustrating a modification of the canvas.

Fig. 7 is a sectional view similar to Fig. 4 illustrating a modified form of union between the end and side rails, particularly adapted for use when the present bed is 35 arranged in tiers.

The present invention is designed primarily to economize storage space in the matter of beds and at the same time provide a durable, comfortable, roomy bed. It has a 40 multitude of uses, such, for instance, in connection with the provision of sleeping accommodations for the crews of dining cars, wreck trains, freight trains, and other railway equipment wherein economy of space is 45 a factor. It can, among other things, be used in conjunction with motor equipment.

In carrying out the present invention tubular end rails are anchored to any suitable 50 fixed support such as the wall of a railroad car or the running board of an automobile

or the wall of a room and between their outer or free ends have a side rail interposed, the end rails supporting a canvas bed. The end rails are also provided with foldable legs at their outer ends which support the end rails 55 and the side rail therebetween when the bed is assembled. When it is desired to collapse the bed the side rail is removed from between the terminals of the end rails and the latter are disengaged from their anchoring structure. This permits the legs to be folded 60 parallel to the side rails and the side rails with their legs rolled into the canvas thereby producing a small, compact bundle made up of the canvas, the legs and the end rails 65 with the side rail separate. Of course, if desired, the side rail may be also collapsed and rolled in the canvas.

Reference being had more particularly to the drawings, 10 designates a supporting 70 wall or structure such as a room wall, the side wall of a railway car or running board of an automobile. Secured to this supporting structure 10 are a pair of brackets 11 spaced one from the other a distance equal to the 75 approximate length of the bed and elevated above the floor or ground a distance equal to the approximate length of the legs, to be described. Each bracket 11 carries a horizontal supporting plate 12 which is provided 80 with a slot or opening 13 therethrough. These brackets 11 and their supporting plates 12 are designed to support the terminals of the end rails of the bed.

Each end rail 14 of the bed constitutes a 85 tube flattened as at 15 at one end and provided with an offset shoulder 16 creating a tongue 17 at the end of the tube. As will be observed from Fig. 5 the tongue 17 rests parallel to the flattened portion 15 of the end 90 rail 14 and is connected thereto by the shoulder which is located at right angles both to the tongue 17 and the flattened portion 15. The width of the flattened portion 15, the 95 tongue 17 and shoulder 16 is such that the tongue and shoulder may be inserted in the opening or slot in the supporting plate 12 of one of the brackets 11. This is accomplished by elevating the end rail 14 to permit the tongue 17 to pass through the opening or slot 100

13 after which the end rail is swung toward a horizontal position whereby the shoulder 16 is permitted to enter and rest in the opening or slot 13. Thus when the end rail is properly positioned, the shoulder 16 rests vertically and passes through the slot or opening 13 while the tongue 17 rests flush against and parallel to the under face of the supporting plate 12 and the flattened portion 15 rests flush against and parallel to the upper surface of the supporting plate 12 on the opposite side of the opening or slot 13. In this manner one end of each end rail 14 is securely anchored to one of the brackets 11 and by it to the supporting structure 10.

At the outer or free end of each end rail 14 opposite the flattened portion 15 is a union 18 which has a reduced shoulder 19 to be received in the end of the cooperating end rail 14. The shoulder 19 has a friction fit in the end of the end rail 14 and is fixedly and rigidly held therein by the rivet or other suitable fastening means 20 passing through the terminal of the end rail 14 and the shoulder 19. Positioned at right angles to the union 19 but in the same plane is a lug 21 provided with a shoulder 22 which constitutes a mounting for one end of the side rail as will be hereinafter more fully described.

The under side of each union is provided with a bracket 23 to which is pivoted a leg 24 and interposed between this leg 24 and the end rail 14 is a foldable brace 25.

From the foregoing it will be seen that each end rail is supported at one end by a bracket 11 and at its opposite end by a leg 24 which may be folded to a position parallel to and flush against the end rail.

A side rail 26 equivalent in length to the length of the bed is interposed between the outer terminals of the end rails 14. This side rail 26 is tubular in construction and is adapted to receive the shoulders 22 of the lugs 21 of the unions 18 and its ends when said side rail is interposed between said unions. If additional security is desired for the connection between the lug 21 and the side rail 26 a pin 27 may be inserted through the end 40 of the side rail 26 and the shoulder 22 of the lug 21. This pin 27 is removably secured in order to permit the disassembling of the bed structure and may be connected by chain 28 to the union 18. A canvas bed 29 is interposed between the end rails 14 and it has a loop 30 formed therein at each end for the reception of the end rails 14.

In assembling the bed the end rails 14 with the canvas 29 secured thereto are mounted on brackets 11 as heretofore described so that they occupy a horizontal plane. When the end rails 14 are so positioned their outer ends, viz; the ends carrying the unions 18, are supported by the legs 24. The side rail 26 may then be interposed between the unions 18 by

springing said end rails outwardly a sufficient distance to permit the side rail 26 to be aligned with the shoulders 22 of the lugs 21 whereby the latter may be received in the ends of the side rail 26. Thus a rigid bed structure is obtained, the length of the side rail 26 being sufficient to maintain the proper tension on the canvas 29.

A modification of the present structure is illustrated in Fig. 6 wherein the canvas is divided into two sections 31 and 32 which are connected by the lacing 33. This modification permits of a regulation of the tension of the canvas between the end rails 14.

When it is desired to disassemble the bed for storage purposes the side rail 26 may be removed from its position between the unions 18 after which the end rails may be disconnected from the plates 12 of the brackets 11. The legs 24 may then be folded against the end rails 14 and the entire structure rolled into the canvas 29. If desired the side rail 26 may be also rolled into the canvas 29 or it may be made in sections which when disassembled may be rolled into the same bundle as the end rails 14 and legs 24. In this manner a compact and relatively small package is produced which can be readily and easily stored in approximately little space.

Should it be desired to arrange beds constructed in accordance with the present invention in tiers, i. e. one above the other, it is only necessary to place additional brackets 11 above and in vertical alignment with the lower brackets 11 and to modify the unions of the lower bed as illustrated in Fig. 7. In the union illustrated in Fig. 7 the body 18 thereof is provided with an upstanding stud 34 on the opposite side thereof to the bracket 23 of the legs 24. This stud is received in the lower ends of the legs 24 of the upper bed which may be tubular for that purpose. This provides a rigid connection between the legs of the upper bed and the structure of the lower bed which prevents any lateral displacement of the legs of the upper bed thereby forming a solid and rigid structure.

It is to be noted that the weight of an occupant on the canvas 29 (31-32) is sufficient to insure the constant connection between the side rail 26 and the shoulders 22 of the unions 18 for the reason that the tendency thereof is to draw the end rails 14 toward one another. This is equally true when the beds are arranged in tiers as the weight of the bed elements of the upper beds, independently of the weight of the occupants, is ample to maintain the legs 24 in engagement with the studs 34.

The present invention, therefore, provides a collapsible bed structure, which may be used singly or in tiers, and yet be rigid and secure when in use. Upon collapsing the bed or beds the elements of each bed may be made into a compact package or bundle for storage.

purposes. In the event the side rail 26 is not stored with the remainder of the bed, a rack may be provided for retaining one or more of them when not in use.

The present bed is capable of many varied uses. It is applicable to railway equipment of all kinds, particularly in dining cars, work or wreck train cars, and cabooses. In dining cars these beds may be used for the accommodation of the crew at night and stored in lockers during the day; in work or wreck cars this is also true and such use will reduce the number of cars required for the accommodation of the crew and laborers; in cabooses the body of the car, which is relatively small, is left free, when the train is in operation. This bed may also be used in bunk houses, even when left up permanently. In short, the present bed may be used wherever there is a mounting for the brackets 11 and while it may be collapsed for storing or moving, it may be left in position if so desired.

What is claimed is:

1. The combination with a fixed bracket, of a tubular end rail having one end thereof flattened and shouldered to create a tongue to one side of and substantially parallel to said flattened portion for cooperation with said bracket, a side rail interposed between the free ends of a pair of said end rails, and a bed carried by said end rails adapted to hold the end and side rails in engagement.

2. The combination with a fixed bracket having an outstanding supporting plate with an opening, of a tubular end rail flattened and shouldered at one end to create a tongue parallel to and at one side of said flattened portion and connected thereto by a right angularly disposed shoulder, said tongue and shoulder being adapted to pass through the opening of said supporting plate whereby the flattened portion rests on one side of said plate and the tongue on the opposite side thereof with the shoulder in the said opening, a union fitted to the opposite end of said end rail provided with a right angularly disposed lug, a bracket on the under side of said union, a leg hinged to said bracket, a folding brace interposed between the leg and the end rail, a side rail interposed between the unions of a pair of the end rails and cooperating with the lugs thereof, and a bed carried between said end rails.

3. The combination with a fixed bracket having an outstanding supporting plate with an opening, of a tubular end rail flattened and shouldered at one end to create a tongue parallel to and at one side of said flattened portion and connected thereto by a right angularly disposed shoulder, said tongue and shoulder being adapted to pass through the opening of said supporting plate whereby the flattened portion rests on one side of said plate and the tongue on the opposite side thereof with the shoulder in the said opening,

a union fitted to the opposite end of said end rail provided with a right angularly disposed lug, a bracket on the under side of said union, a leg hinged to said bracket, a folding brace interposed between the leg and the end rail, an upstanding stud on the upper side of said union for cooperation with a leg of a superimposed bed structure, and a flexible bed element interposed between said end rails.

4. The combination with a fixed bracket having an outstanding supporting plate with an opening, of a tubular end rail flattened and shouldered at one end to create a tongue parallel to and at one side of said flattened portion and connected thereto by a right angularly disposed shoulder, said tongue and shoulder being adapted to pass through the opening of said supporting plate whereby the flattened portion rests on one side of said plate and the tongue on the opposite side thereof with the shoulder in the said opening, a union fitted to the opposite end of said end rail provided with a right angularly disposed lug, a bracket on the under side of said union, a leg hinged to said bracket, a folding brace interposed between the leg and the end rail, a stud on the upper side of said union for engagement by a leg of a similar superposed bed structure, and a canvas suspended between said end rails.
